(57) **CLAIM**

The ornamental design for a diaper leak pad, substantially as shown and described.

DESCRIPTION

FIG. 1 is a perspective view of a diaper leak pad according to the present invention and shown in the exemplary environment of being folded and attached to the outside, front of a baby diaper;

FIG. 2 is a perspective view of the diaper leak pad of FIG. 1 in a partially folded configuration;

FIG. 3 is a front plan view of the diaper leak pad of FIG. 1 in an unfolded configuration;

FIG. 4 is a rear plan view of the diaper leak pad of FIG. 1 in an unfolded configuration;

FIG. 5 is a top side elevation view of the diaper leak pad of FIG. 1 in an unfolded configuration;

FIG. 6 is a bottom side elevation view of the diaper leak pad of FIG. 1 in an unfolded configuration;

FIG. 7 is a left side elevation view of the diaper leak pad of FIG. 1 in an unfolded configuration; and

FIG. 8 is a right side elevation view of the diaper leak pad of FIG. 1 in an unfolded configuration.

FIG. 9 is a perspective view of a diaper leak pad according to the present invention and shown in the exemplary environment of being folded and attached to the inside, front of a baby diaper;

FIG. 10 is a perspective view of the diaper leak pad of FIG. 9 in a partially folded configuration;

FIG. 11 is a front plan view of the diaper leak pad of FIG. 9 in an unfolded configuration;

FIG. 12 is a rear plan view of the diaper leak pad of FIG. 9 in an unfolded configuration;

FIG. 13 is a top side elevation view of the diaper leak pad of FIG. 9 in an unfolded configuration;

FIG. 14 is a bottom side elevation view of the diaper leak pad of FIG. 9 in an unfolded configuration;

FIG. 15 is a left side elevation view of the diaper leak pad of FIG. 9 in an unfolded configuration; and,

FIG. 16 is a right side elevation view of the diaper leak pad of FIG. 9 in an unfolded configuration.

The broken lines shown in FIGS. 2-8, FIG. 10 and FIGS. 12-16 illustrate portions of the diaper leak pad that form no part of the claimed design. The additional broken lines shown in FIGS. 1 and 9 illustrate environment and form no part of the claimed design.

1 Claim, 12 Drawing Sheets
